UNITED STATES PATENT OFFICE.

JOHN C. MOSS, OF ROSSTON, TEXAS.

COMBINED PLOW, HARROW, AND CULTIVATOR.

SPECIFICATION forming part of Letters Patent No. 257,365, dated May 2, 1882.

Application filed September 29, 1881. (Model.)

To all whom it may concern:

Be it known that I, JOHN C. MOSS, a citizen of the United States, and a resident of Rosston, in the county of Cooke and State of Texas, have 5 invented a new and valuable Improvement in Combined Breaking-Plows, Harrows, and Cultivators; and I do hereby declare that the following is a full, clear, and exact description of the construction and operation of the same, 10 reference being had to the annexed drawings, making a part of this specification, and to the letters and figures of reference marked thereon.

Figure 1 of the drawings is a representation of a plan view of the device used as a cultivator. 15 Fig. 2 is a longitudinal vertical section of Fig. 1. Fig. 3 is a plan view of the device used as a harrow, and Fig. 4 is a rear elevation of the same.

This invention has relation to combined 20 plows, cultivators, and harrows; and it consists in the novel construction and arrangement of parts, as will be hereinafter fully described, and particularly pointed out in the claim.

25 Referring by letter to the accompanying drawings, A designates the frame, composed of the cross-beam B, uprights C C, side beams, D D, and perforated draft-bar E, connecting the front ends of side beams, D D. A curved strap, F, rises from the forward ends of the side beams, D D, to a height on a level with the cross-beam B, and upon this and the cross-beam B the tongue G is secured. Braces H H extend from near the bases of the uprights C C 30 to the cross-beam B at its junction with the tongue G. Braces I I extend from the side beams, D D, to the curved strap F, as shown. Curved braces J J are secured to the inner faces of the side beams, D D, and extend backward, and are supported by braces K K, extending up to the tongue, as shown. Pivoted perforated arms L L are journaled in the side beams, D D, and the curved braces J J, and form the connections for the cultivator-beams 35 M M, which are bifurcated in their forward ends and may be adjusted laterally on the arms L L. A plow-beam, N, is secured to the perforated strap or metal beam E, is provided with a clevis, and may be laterally adjusted 40 thereon. The rear end of the plow-beam N is pivoted in supporting-straps O O, perforated at their upper ends and connected by a bolt,

P, to a lever, Q, having its fulcrum at the rear end of the tongue G. The tongue G is provided with a pivoted pendulant arm, R, the 55 foot of which rests upon the tongue when it is necessary to elevate the plow from the ground, but which lies flatly on the tongue when the plow is in use. The side beams, D D, are provided with double bearings S S in front of the 60 uprights C C, for the reception of the journals T of the harrow-wheels U during the time the implement is to be used as a plow or cultivator. Double bearings V V are also provided, the 65 upper portion of the bearings being secured to the rear faces of the uprights C C and the lower portions thereof to the under faces of the side beams, D D, at their rear ends, as shown, for the reception of the journals of the harrow-wheels U when the implement is to be converted into a rotary harrow. The lever Q is 70 employed to elevate the plow-beam N when the cultivators are to be used.

When the implement is to be used as a harrow the wheels having the laterally-projecting 75 teeth a are removed from the double bearings S S and the journals T are inserted into the double bearings V V. The journals T are perforated near their inner ends, and keys of ordinary construction are employed to hold them 80 in place in either of the bearings.

From the foregoing it will be seen that the implement may be used as a breaking-plow, a cultivator, or a rotary harrow.

Having thus fully described my invention, 85 what I claim as new, and desire to secure by Letters Patent, is—

In a combined implement, the frame A, composed of the cross-beam B, uprights C C, side beams, D D, and draft-bar E, the frame being 90 provided with the horizontal double bearings S S and the vertical double bearings V V, the curved braces J J, and the perforated pivoted arms L L, adapted for interchangeably connecting thereto the breaking-plow, the cultivators, and the harrow-wheels, substantially 95 as specified.

In testimony that I claim the above I have hereunto subscribed my name in the presence of two witnesses.

JOHN C. MOSS.
